UNITED STATES PATENT OFFICE.

JOSIAS R. KING, OF ST. PAUL, MINNESOTA, ASSIGNOR OF ONE-HALF HIS
RIGHT TO WILLIAM M. TILESTON, OF NEW YORK, N. Y.

DESIGN FOR EMBLEMATIC VASE.

Specification forming part of Design No. **7,807**, dated October 27, 1874; application filed September 15, 1874.
[Term of Patent 7 years.]

To all whom it may concern:

Be it known that I, JOSIAS R. KING, of the city of St. Paul, county of Ramsey and State of Minnesota, have invented a Design for an Emblematic Vase or Holy-Water Vessel, of which the following is a specification:

The nature of my design is fully represented in the accompanying drawing, to which reference is made.

A represents a cross, having the initials I. H. S. B represents a flame, into which the cross A is inserted. C represents a cover to the part D, and upon the top of which rests the flame B. D represents the body of the vessel, made of any suitable material, and in the form and shape of a human heart. E represents a crown of thorns woven around the base of the body, forming a receptacle for such base to rest upon, and into which the vessel is inserted.

The crown may be composed of willow wood or other suitable material.

F represents the base upon which the vessel and crown rest, and which may bear upon its front the words "Holy Water," or any other appropriate inscription, the whole forming a new, useful, and ornamental design.

I am aware of the fact that the cross, flame, heart, and crown are found together on lithographic and steel prints; but I am not aware of said emblems ever having been combined in the manner and for the purpose described by me.

What I claim as my invention, therefore, is—

The emblematic vase or design for a holy-water vessel, substantially as herein shown and described.

JOSIAS R. KING.
